UNITED STATES PATENT OFFICE.

PETER T. POTTS, OF CHICAGO, ILLINOIS, ASSIGNOR TO THE VORTEX MFG. CO., A CORPORATION OF ILLINOIS.

SANITARY SUNDAE-CUP HOLDER AND DISPENSER.

1,424,517.

Specification of Letters Patent. Patented Aug. 1, 1922.

Application filed February 28, 1921. Serial No. 446,824.

To all whom it may concern:

Be it known that I, PETER T. POTTS, a citizen of the United States, and a resident of the city of Chicago, in the county of

5 Cook and State of Illinois, have invented certain new and useful Improvements in a Sanitary Sundae-Cup Holder and Dispenser; and I do hereby declare that the following is a full, clear, and exact description of the same, reference being had to the accompanying drawings, and to the numerals of reference marked thereon, which form a part of this specification.

10 This invention relates to improvements in holders and dispensers for paper cups used for serving sundaes or the like at soda fountains or other similar places and has for one of its objects the provision of a sanitary dust-proof holder for such paper cups 15 or receptacles and one from which the same may be readily removed with a minimum expenditure of time and trouble.

20 Another object of the invention is the provision of a sanitary holder and dispenser for cups or the like which is absolutely dust-proof and which forms a neat and attractive receptacle and which is moreover compact and is adapted to be positioned so as to be always within the ready reach of the attendant at the fountain and conveniently accessible without detracting from the neat orderly appearance of the establishment.

25 A still further object of the invention is the provision of a convenient, durable and attractive dispenser or container especially adapted for the dispensing of paper or other flexible nested cups and which is arranged to prevent any contact of the hands of the attendant with the cups.

30 Still another important object of the invention is the provision of a sanitary sundae cup holder and dispenser wherein the blanks are kept clean and free from dust and are so positioned that they cannot be 35 touched or handled except by withdrawing them singly and in a particular manner.

35 Other and further important objects of this invention will be apparent from the disclosure in the accompanying drawings and specification.

The invention (in a preferred form) is shown in the drawings and hereinafter more fully described.

On the drawings:

Figure 1 is a top plan view of the combined holder and dispenser showing the same in closed position. 55

Figure 2 is a side elevation of the same in open position.

Figure 3 is a side elevation of the holder and dispenser in closed position. 60

Figure 4 is a partial sectional view taken on the line 4—4 of Figure 3.

Figure 5 is a detail sectional view taken on the line 5—5 of Figure 1. 65

As shown on the drawings:

The reference numeral 10 indicates the base of the holder or container or dispenser which may be made of any suitable material and which is preferably circular in form 70 and has fixed thereon an inner containing member 12 approximately semi-cylindrical in form. This member 12 is in the shape of a cylinder with a portion cut away as is best shown in Figure 2. An approximately 75 semi-circular top 14 is provided for the member 12 and is fastened thereto in any approved manner such as by soldering or brazing. A portion of the top 14 is cut away to correspond with the opening in the 80 cylinder 12. Rotatably mounted in a hole in the center of the top 14 is a pin 16 having at its upper end a knurled knob or handle 18. The pin 16 and the handle 18 are attached to the center of a corresponding top 85 20 which is also slightly more than semi-circular in form and which forms the top of a corresponding cut away cylinder 22 which is preferably slightly larger than the cylinder 12 and adapted to fit there- 90 around. A washer or similar member 24 is positioned around the pin 16 and between the covers or plates 14 and 20 so as to permit easy turning of the plate 20 with respect to the plate 14. 95

The outer cylindrical member 22 is cut away to correspond with the cut-away portion of the inner cylinder 12 as is best shown in Figures 2 and 3, the lower portions of both the cylinders being extended around 100

the circle to a greater degree than the top-most portion so that the cups or sundae holders may be positively retained within the lower portion of the dispenser. The 5 cups are represented at 26 and a metallic holder 28 is shown in position in the dispenser or container ready for the withdrawal of a cup 26 therefrom. A stop 30 10 12 in any suitable manner so as to prevent any excess motion of the outer cylinder 22 when the container is closed.

The operation is as follows:

A suitable number of sundae or similar 15 dishes 26 are inserted into the cylinder 12 with a holder 28 positioned upon the top thereof as shown in Figure 2. This holder is of the type shown and described in U. S. Patent No. 1,280,416 granted to David F. 20 Curtin on October 1st, 1918, and operates in the manner described in said patent, wherein the topmost dish is removed from the stack by rotating the holder so as to engage the tongue or lip of the blank by 25 an inwardly projecting tongue on the holder.

The container or dispenser is readily opened by merely manipulating the knurled knob 18 upon the top thereof whereupon the 30 outer cylinder 22 revolves on the pin 16 and its open portion comes into alinement with the open portion of the inner cylinder 12 leaving the device in the position shown in Figure 2 when a cup 28 may be readily 35 taken therefrom by means of the holder 28 or in any other suitable manner. After the cup has been withdrawn a reverse rotation of the knob 18 will serve to close the container and bring the respective cylinders to 40 the position shown in Figure 3 whereupon a dust-proof and absolutely sanitary cup holder results.

It will be seen that herein is provided a 45 container and dispenser for sundae cups which is of neat appearance and is absolutely dust-proof and which can be mounted in position upon the counter of a soda fountain or similar establishment and will add greatly to the attractiveness of same as the 50 container may be made in various shapes and sizes and may be ornamented if desired. The device herein shown is particularly desirable on account of the cleanly and efficient manner in which the cups or sundae holders 55 are handled thereby as there is absolutely no possibility of contact of hands of the attendant with the interior of the cups, or of any portion of the cup.

I am aware that many changes may be 60 made and various details of construction modified without departing from the spirit of the invention, and I therefore do not purpose limiting the patent granted hereon otherwise than necessitated by the prior art.

65 I claim as my invention:

1. A container and dispenser for paper cups including a pair of cylinders concentrically mounted, one of said cylinders being relatively fixed and the other adapted to rotate about their common axis, and openings in said cylinders through which a cup is adapted to be withdrawn, together with means for alining said openings. 70

2. A container and dispenser for paper cups including a base, a cylindrical member 75 mounted thereon, said member being open at one side thereof, and a closure means for said opening, said closure means including an outer cylinder mounted concentrically with the first and provided with a corresponding opening, together with means for alining said openings. 80

3. A container and dispenser for paper cups including a pair of cylinders concentrically mounted, one of said cylinders being relatively fixed and the other adapted to rotate about their common axis, and openings in said cylinders through which a cup is adapted to be withdrawn, together with means for alining said openings, and means 85 for limiting the relative motion of the cylinders. 90

4. A container and dispenser for paper cups including a base, a cylindrical member 95 mounted thereon, said member being open at one side thereof, and a closure means for said opening, said closure means including an outer cylinder mounted concentrically with the first and provided with a corresponding opening, together with means for 100 alining said openings, and means for limiting the relative motion of the cylinders.

5. A container and dispenser for paper cups including a pair of cylinders concentrically mounted, one of said cylinders being relatively fixed and the other adapted to rotate about their common axis, and openings in said cylinders through which a cup is adapted to be withdrawn, together with means for alining said openings, the openings in said cylinders being so shaped as to provide for the free withdrawal of the cups 110 at the top portion of the container only. 105

6. A container and dispenser for paper cups including a base, a cylindrical member 115 mounted thereon, said member being open at one side thereof, and a closure means for said opening, said closure means including an outer cylinder mounted concentrically with the first and provided with a corresponding opening, together with means for alining said openings, the openings in said cylinders being so shaped as to provide for 120 the free withdrawal of a cup from the top portion of the container only. 110

7. A container and dispenser for cups comprising a base, a curved member secured thereon and having an opening therein, an apertured cover rigidly secured on the upper end of said curved member, a curved closure 125

member movably mounted to the outside of said curved stationary member and having an opening therein, a cover plate secured upon the top of said closure member, a pin 5 secured to said cover plate and projecting through the aperture in said apertured cover, and a knob secured to said pin to permit operation of the curved closure member.

8. A container and dispenser for cups 10 comprising a stationary casing member having an opening therein, a rotatable casing member disposed to the outside of said stationary casing member and also having an opening therein, and a knob on said rotatable casing member to operate the same to 15 open and close the opening in said stationary casing member.

9. A container and dispenser for cups 20 comprising a stationary casing member having a restricted opening therein, a rotatable

casing member disposed to the outside of said stationary casing member and also having a restricted opening therein, means for rotating the rotatable casing member, and a stop on said stationary casing member projecting through the opening in said rotatable casing member. 25

10. A container and dispenser for cups comprising a pair of relatively movable casing members having openings therein restricted at their lower portions to permit cups to be withdrawn through the upper portions of said openings only. 30

In testimony whereof I have hereunto subscribed my name in the presence of two sub- 35 scribing witnesses.

PETER T. POTTS.
